H. M. BURROWS, OF NORWICH, NEW YORK.

Letters Patent No. 89,735, dated May 4, 1869.

IMPROVEMENT IN PATTERNS, MEASURING, AND LAYING OUT LADIES' DRESSES.

The Schedule referred to in these Letters Patent and making part of the same.

To all whom it may concern:

Be it known that I, H. M. BURROWS, of Norwich, Chenango county, and State of New York, have invented a new Mode of Cutting and Fitting Ladies' and Misses' Dresses; and I do here declare that the following is a full, complete, and exact description thereof, reference being had to the accompanying drawings, and to the letters and figures marked thereon.

The nature of my invention consists of a diagram or design, and I will here state its advantages over all others.

First, it gives a broad front and narrow back, which is indispensable for a stylish fit, while all others give a contracted front and broad back. The method by which the broad front is fitted to a narrow back, is by means of small seams taken on shoulder of front, which no other rule of cutting admits of.

Second, it gives a perfect guide for forming the darts on front, without taxing the skill or judgment of the cutter. The dots are so graduated as to fit the largest as well as the smallest form, while all other rules leave this entirely to the judgment of the dress-maker.

To enable others skilled in the art to use my invention, I will proceed to describe the mode of measuring and draughting.

In order to cut a waist of a dress, the following measures are obtained:

First. Chest-measure by passing the tape-measure under the arms, just below shoulder-blade, bringing it tightly over the largest part of the bust.

Second. Measure tightly around the waist.

Third. Place the tape under the arm-pit, and measure straight down to bottom of waist.

These measures being obtained, to draught a front, I double the cloth with selvages together, and fold over one and a half inch for hooks and eyes. Place line A of chart on the folded edge of the cloth.

Suppose a lady's measure to be, chest 34, waist 24, length of waist, from arm-pit to waist, 8.

First, dot in upper neck-circle.

Second, dot holes o at each end of the line, marked "short seam."

Third, dot in 34 upon front shoulder-line; also in 34 on chest-line, and 34 on dart-line, and remove chart.

Take dart-measure, place the point at the 34 dot, in front of shoulder-line, and carry the straight edge to upper dot of neck-circle, (which brings dart-measure with wrong side up.) Place dart-measure inside the darts, on front shoulder-line, not above them, then line from one to the other, and cut one inch above for seam.

Take large arm-size, place figure 34 of straight edge of arm-size upon dot made at 34 on front shoulder-line, and swing it around until the dot on chest-line comes into the slash of arm-size.

Then line around from 34 on the straight edge of arm-size, to short line on curved edge of arm-size, on which is found figure 34. Take square end of D-measure, place at the lowest part of the curve of arm-size, and measure straight down, and dot at figure 8 for length of waist.

Place the square end of D-measure at the front edge

of cloth, with the straight edge down even with dot made for length of waist, and have a straight line across the width of cloth for bottom of waist. Next place point of D-measure at dot on dart-line, one and a half inch from the edge of the cloth at bottom; mark on curved edge of D-measure from the point to bottom of waist; also dot in holes of D-measure; this gives the first dart.

Next place point of D-measure three and a half inches from top of first dart, and a half inch apart at the bottom, and line on both sides of D-measure for second dart. Reserve one-fourth of ladies' measure around the waist for back.

In this case, the measure is 24; therefore eighteen inches must be left for fronts. There is one and a half inch forward of first dart; one inch of this is used by lappings; the remaining half inch added to the half-inch between darts, leaves eight inches back of second dart. Make a dot eight inches back of second dart, on the line of bottom of waist; if the cloth is not sufficiently broad, it must be pieced. Place the curve at the lowest, 34, dot, (made in marking around arm-size,) and carry down to dot last made at bottom of waist; draw a line, and cut one inch beyond for seam.

Rule for Draughting Back.

Turn the cloth with the whole edge toward you, leaving it double. Place the chart with line A upon the cloth the whole edge. First make a line across back of neck from 1 to 2. Now dot in 32 on back shoulder-line, which gives two sizes less on back than front, in order to give a narrow back. Next dot in 33, on line marked "back arm-size." Then place line B at the dots, and mark from one to the other. Now place point of dart-measure at the 32 dot on back shoulder-line, and carry straight edge to figure 2 dot on back of neck; draw a line on upper edge of measure; cut one inch outside for seam; take square end of D-measure, place at lowest dot on back, and make a dot at 8 for length of back. Place D-measure with square end toward you, straight across from dot just made and dot at figure 3.

Line straight across the cloth, toward you from bottom of waist. Place the point of D-measure at dot on back arm-size and carry to 3 dot, and line on curved side; cut one inch outside this line, or under arm-seam. Take back-form, place small holes in line with 33 dot on back arm-size, and bring down lower part of waist a half inch from edge, and line upon the upper edge.

Having described my mode of cutting and fitting ladies' and misses' dresses, I make the following

Claim.

What I claim as new, and wish to secure by Letters Patent of the United States, is—

The chart, diagram, or design for cutting and fitting ladies' and misses' dresses, substantially and for the purposes above described and set forth.

H. M. BURROWS.
